[57] CLAIM

The ornamental design for the toner bottle, as shown and described.

DESCRIPTION

FIG. 1 is a perspective view of the toner bottle showing our new design, the broken line(s) showing of a toner bottle is for environmental purposes only and form no part of the claimed design;

FIG. 2 is a front elevational view thereof;

FIG. 3 is a left side elevational view thereof;
FIG. 4 is a right side elevational view thereof;
FIG. 5 is a rear side elevational view thereof;
FIG. 6 is a top view thereof;
FIG. 7 is a bottom view thereof;
FIG. 8 is a perspective view of a second embodiment of our new design, the broken line(s) showing of a toner bottle is for environmental purposes only and form no part of the claimed design;
FIG. 9 is a front elevational view of the embodiment of FIG. 8;
FIG. 10 is a left side elevational view of the embodiment of FIG. 8;
FIG. 11 is a right side elevational view of the embodiment of FIG. 8;
FIG. 12 is a rear elevational view of the embodiment of FIG. 8;
FIG. 13 is a top view of the embodiment shown in FIG. 8;
FIG. 14 is a bottom view of the embodiment shown in FIG. 8;
FIG. 15 is a perspective view of a third embodiment of our new design, the broken line(s) showing of a toner bottle is for environmental purposes only and form no part of the claimed design;
FIG. 16 is a front elevational view of the embodiment of FIG. 15;
FIG. 17 is a left side elevational view of the embodiment of FIG. 15;
FIG. 18 is a right side elevational view of the embodiment of FIG. 15;
FIG. 19 is a rear elevational view of the embodiment of FIG. 15;
FIG. 20 is a top view of the embodiment shown in FIG. 15; and,
FIG. 21 is a bottom view of the embodiment shown in FIG. 15.
